UNITED STATES PATENT OFFICE.

FRIEDRICH SCHWITALLA, OF SCHWIENTOCHLOWITZ, AND PAUL FIEBIG,
OF ANTONIENHÜTTE, GERMANY.

AIR-DOOR.

SPECIFICATION forming part of Letters Patent No. 743,572, dated November 10, 1903.

Application filed November 12, 1902. Serial No. 131,053. (No model.)

To all whom it may concern:

Be it known that we, FRIEDRICH SCHWITALLA, residing at Schwientochlowitz, and PAUL FIEBIG, residing at Antonienhütte, 5 Silesia, Germany, subjects of the German Emperor, have invented an Improved Air-Door, of which the following is a full, clear, and exact description.

The present invention relates to air-doors, 10 and has for its purpose to open and close them automatically.

The improved door may be used in water-level drifts as well as for transportation on an inclined plane by means of a rope or a chain, 15 no matter from which direction the truck approaches.

In order to render the present specification more easily intelligible, reference is had to the accompanying drawings, in which—

20 Figure 1 is a longitudinal section of the door. Fig. 2 is a horizontal section on line A B of Fig. 1, the rails at the left-hand side being shown in dotted lines. Fig. 3 is a section on line C D of Fig. 2 looking toward the 25 doors, and Fig. 4 shows the operating mechanism on an enlarged scale.

According to the present invention the door is automatically opened in that the rails on which the truck is running are lowered by 30 means of the weight of the said truck. For this purpose the rails *a* are pivotally mounted on a cross-bar *b* and rest loosely on a cross-beam *c*, which is securely fixed to the lower plate *d*. The plate *d* is pivotally connected with the 35 two-armed lever *e*, Fig. 4, which has its fulcrum at *f*. An adjustable weight *g* is arranged at the longer arm of the said lever, while the other end is connected with rails *i* by means of a connecting-link *h*, said rails 40 being also mounted to swing vertically similarly to the rails *a*.

The two leaves of the door are curved to the arc of a circle in cross-section and swing on upper and lower trunnions, forming the 45 center of such circle when opened or closed. This rotary movement is attained in that each door-leaf *k* is supported on sectors at the top

and bottom, the upper sectors being pivotally supported on trunnions *m*, which lie in the center of the arc of the circle, while the 50 lower sectors *n* are supported on twisted edged bolts *o*, such bolt *o* being revoluble on the supporting-plate *p*. The twisted edged bolt *o* thus constitutes a screw with very high pitch and is guided through the female 55 thread of the plate *d*. If now the plate *d* is moved downward by the rails *a* or *i* being loaded, the bolts *o* are turned, owing to the high pitch, and with them the door-leaves *k*, so that the latter are turned around the 60 center of the arc of their circle—viz., are opened outwardly. The truck may now pass through the open door from the rails *a* to the rails *i*, or vice versa. As soon as the rails are relieved of their weight they are raised again, 65 together with the plate *d*, either by spring action or by means of the counterweight *g*, so that by this reverse movement of the plate *d* a reverse movement of the two twisted bolts *o*, and thus of the door-leaves, takes place, 70 which latter now approach each other again and close the door.

We claim as our invention—

1. The combination of a pair of doors curved to the arc of a circle and having upper and lower sectors attached thereto, with upper and lower pivots forming the center of the said arc, and on which the said doors swing apart, vertically-movable rail ends leading up to the said doors from both sides in alignment, and means for swinging the said doors apart when one of the said movable rail ends is loaded, and for swinging the doors back in the closed position when the load passes off the movable part of the rails substantially as 85 described.

2. The combination of a pair of doors curved to the arc of a circle and upper and lower sectors having supporting-pivots for said doors in the center of the said arc, the said lower 90 pivots consisting of twisted edge bolts, an internally-threaded plate to engage the said twisted edge bolts, said plate being vertically movable, vertically-movable rail or track ends

leading up to either side of said doors and means in connection with the same for depressing the said internally-threaded plate when one of the track ends is loaded and for 5 automatically returning the said plate and closing the doors when the rail or track ends are unloaded substantially as described.

In witness whereof we have hereunto set our hands in presence of two witnesses.

FRIEDRICH SCHWITALLA.
PAUL FIEBIG.
